COASTER OR SIMILAR ARTICLE

Aristodeme J. Cosmetto, Rye, N. Y.

Application March 11, 1953, Serial No. 23,997

Term of patent 14 years

(Cl. D44—10)

To all whom it may concern:

Be it known that I, Aristodeme J. Cosmetto, a citizen of the United States, residing in Rye, county of Westchester, and State of New York, have invented a new, original, and ornamental Design for a Coaster or Similar Article, of which the following is a specification, reference being had to the accompanying drawings, forming a part thereof, in which:

Fig. 1 is a top plan view of a coaster or similar article showing my new design; and

Fig. 2 is a side elevational view thereof;

Fig. 3 is a cross-sectional view taken on lines 3—3 of Fig. 1.

I claim:

The ornamental design for a coaster or similar article, as shown.
